CLAIM

The ornamental design for combined golf ball and model aircraft engine novelty device, substantially as shown and described.

DESCRIPTION

FIG. 1 is a side elevational view of a combined golf ball and model aircraft engine novelty device showing my new design.

FIG. 2, an front end elevational view of the design;

FIG. 3, a side elevational view of the design;

FIG. 4, a rear end elevational view of the design;

FIG. 5, a top plan view of the design; and

FIG. 6, a bottom plan view of the design.

The dimples on the golf ball are conventional, but are shown fragmentarily in each figure for convenience of illustration.
